UNITED STATES PATENT OFFICE.

VICTOR MARKKULA, OF ABERDEEN, WASHINGTON.

WEATHER-VANE INDICATOR.

1,219,126.

Specification of Letters Patent. Patented Mar. 13, 1917.

Application filed May 26, 1916. Serial No. 100,134.

To all whom it may concern:

Be it known that I, VICTOR MARKKULA, a citizen of the United States, residing at Aberdeen, in the county of Chehalis and 5 State of Washington, have invented certain new and useful Improvements in Weather-Vane Indicators; and I do hereby declare the following to be a full, clear, and exact 10 description of the invention, such as will enable others skilled in the art to which it appertains to make and use the same.

This invention has for its object to provide an improved weather vane indicator of simple and efficient construction embodying 15 essentially a vertically disposed shaft, a vane connected with the upper extremity of said shaft and an indicator operatively connected with the lower end of said shaft.

With this and other objects in view, the 20 invention consists in the novel construction, combination and arrangement of parts as will be hereinafter specifically described, claimed and illustrated in the accompanying drawing, in which:

25 Figure 1 represents a front elevation of the improved weather vane,

Fig. 2 represents a side elevation thereof,

Fig. 3 represents a fragmentary vertical sectional view on the line 3—3 of Fig. 1, and

30 Fig. 4 represents a horizontal sectional view on the line 4—4 of Fig. 3.

Referring to the drawing in detail, wherein similar reference numerals designate corresponding parts throughout the several 35 views, the numeral 5 indicates generally a casing or housing including a top 6, bottom 7, rear wall 8, side walls 9, and a front plate 10. The side walls 9 are formed with openings 11 to permit access to the mechanism 40 contained within the casing and the openings may be closed by doors 12, hingedly secured to the side walls and adapted to be locked in closed position by latches 13.

A supporting frame, preferably constructed 45 of metal, is mounted within the casing 5 and includes a base plate 14 supported upon the bottom 7 of the casing and having integral upstanding reinforcing flanges 15. Adjacent the front of the casing the base plate 50 14 is provided with upstanding parallel standards or uprights 16, and at the rear edge of said base plate is formed an up-

standing upright 17. The central portion of the base plate is recessed, as indicated at 18, to receive the lower tapered extremity of 55 a vertically disposed shaft 19 which extends upwardly through the top 6 of the casing and is provided at its upper terminal with a vane 20.

A dial 22 is set into the front plate 10 of 60 the casing and receives a shaft 23 carrying an indicator hand 24, which latter is movable over the dial 22 and is adapted to contact therewith to indicate the direction in which the wind is blowing, the dial being 65 suitably marked, as clearly shown in Fig. 1, to assist in ascertaining the direction of the wind. The rear portion of the shaft 23 is rotatably supported in the uprights 16 and is rigidly connected with a pinion 25, which 70 meshes with a pinion 26 mounted upon an intermediate shaft 27, which latter is also rotatably supported in the uprights 16 and is provided at its rear end with a bevel gear wheel 28. The gear wheel 28 meshes with a 75 similar gear wheel 29 adjustable vertically upon the shaft 19, whereby rotary movement is transmitted from the shaft 19 through the bevel gear wheels 29 and 28, intermediate shaft 27, pinions 26 and 25, shaft 80 23 to the hand 24.

Intermediate the base plate 14 and the casing top 6, the shaft 19 is rotatably supported in an adjustable bearing plate 30, which is positioned upon the uprights 16 85 and 17, and is provided with depending lugs 31, which engage the innermost upright 16 and the upright 17. Lugs 31 are secured to the uprights 16 and 17 by screws 32, which may be adjusted to move the bearing plate 90 30 forwardly and rearwardly with relation to the upright 17 and thus compensate for wear upon the bevel gear wheels 28 and 29.

What I claim is:

A weather vane indicator comprising a 95 casing, a frame mounted in said casing and including a base plate, and a plurality of uprights supported upon said base plate, a dial positioned upon the front of said casing, a shaft rotatably supported in said frame and projecting upwardly through said casing, an indicator shaft rotatably supported in several of said uprights, a hand carried by said shaft and movable over said 100 105

dial, an intermediate shaft rotatably supported in several of said uprights and arranged below the indicator shaft, means connecting said indicator and intermediate shafts, bevel gear wheels connecting said vertical shaft with the intermediate shaft, an adjustable bearing plate supported upon said uprights and rotatably receiving said

vertical shaft, and means for adjusting said bearing plate.

In testimony whereof I affix my signature in presence of two witnesses.

VICTOR MARKKULA.
